CHASE HOOK FOR PRINTING PRESSES

Abel Kluge, Woodbury Township, Washington County, Minn., assignor to Brandtjen and Kluge, Inc., St. Paul, Minn., a corporation of Minnesota

Application October 6, 1951, Serial No. 250,104

7 Claims. (Cl. 101—391)

1

My invention relates to improvements in chase hooks for printing presses.

In the conventional platen printing press of the Gordon type with which this invention is particularly concerned, a chase or frame for the type used in producing the printing impression is mounted on the bed of the press. Ordinarily the bottom rail of the chase rests on bottom stops fixed to the press bed, while the top rail of the chase is releasably engaged by a movable chase-locking hook or the like carried by the bed.

A press operator is confronted with a laborious task in lifting a leaded chase into and out of place on the bed of a press with two otherwise unengaged hands and that task is rendered exceedingly difficult when one or the other of the operator's hands becomes necessarily occupied in manipulating a chase hook while the chase is being placed on or removed from the press bed.

The present demand for ease and speed in production calls not only for lightening the burden of a press operator, but also in quickening his work in applying a chase to and removing the same from the bed of a press.

To such ends and for other purposes, it is an object of my invention to provide a simple, durable and relatively inexpensive chase hook which is readily applicable to the bed of a printing press, which is unfailingly capable of holding a leaded chase firmly and securely in place on the bed during press operation, which is adapted to be quickly and easily locked and unlocked and in each case by a single movement of one hand, which when locked tends automatically to increase the force holding the chase in place on the bed, and which when unlocked remains securely in such condition unobstructing the path of a chase being passed to or from the bed.

Other objects of the invention reside in the novel combination and arrangement of parts and in the details of construction hereinafter illustrated and/or described.

In the drawings:

Fig. 1 is a side elevational view of a chase hook constructed in accordance with my invention, the same being shown as partly broken away and as applied to the bed of a platen press, said bed and a chase thereon being illustrated in vertical section as on the line 1—1 of Fig. 2.

Fig. 2 is a plan view of the chase hook structure, press bed and chase shown in Fig. 1, the bed and chase being illustrated fragmentarily.

Reference being had to the drawing, it will be seen that the bed of the printing press therein illustrated is designated by the reference numeral

2

10 while the chase shown as applied to said bed is designated in its entirety by the reference letter A. Conventionally, the lower rail 11 of the chase A has a beveled surface 12 extending along the lower outer portion thereof. This beveled surface 12 is adapted to engage a complementally beveled surface 13 on each of two relatively spaced bottom stops 14 each of which is fastened as by means of a bolt 15 to the press bed 10. With said lower rail 11 of the chase A bearing against said bottom stops 14, said chase, particularly at the lower portion thereof, is firmly backed against the face 10a of the bed 10.

The chase hook of the present invention releasably engages the upper rail 16 of the chase A in a manner firmly clamping the upper portion of the chase back against the face 10a of the bed 10 and at the same time solidly wedging the lower rail 11 of the chase A against the bottom stops 14 on the bed 10.

In the illustrated embodiment of my invention, a mounting B is supplied, the same consisting of a pair of brackets 17 each having an attaching flange 18 thereon adapted to be secured to the back of the upper portion of the press bed 10 as by means of screws 19. Attached to the bed 10, the brackets 17 extend rearwardly therefrom in relatively spaced relation. Extending through said brackets 17 beneath the ends thereof is a pivot bolt 20. On this bolt 20, a latch lever C is intermediately pivoted, said latch lever C having a forward arm 21 and a rearward arm 22, the former forwardly overreaching the upper edge of the bed 10 and the latter extending rearwardly therefrom. At the extremity of the forward arm 21 is a downturned catch 23 having a biased bearing surface 24 complementing and adapted to engage the beveled surface 25 of the upper rail 16 of chase A. At the lower edge of the rearward arm 22 of said latch lever C, said arm 22 has a low bearing surface 26 rearwardly thereof, while forwardly of said low bearing surface 26 said arm 22 has a high bearing surface 27. Between said bearing surfaces 26, 27 and jogging from one to the other thereof said rearward arm 22 has a riser surface 28 forming an abutment which is herein at times referred to as a riser-abutment.

To the rear of the latch lever C is a cam 29 of generally segment-like form, the same having a mounting boss 30 formed with a bore 31 therein. A cam shaft 32 is journaled at its inner end in both of the brackets 17 and that portion of said cam shaft 32 between said brackets is received in the bore 31 of the cam boss 30, said boss being keyed to said cam shaft 32 as by means of key-

pin 33. At the outer end of the cam shaft 32, which preferably extends to a point even with the side of the press bed 10, said cam shaft 32 is fitted with a finger piece in the form of a pin 34 for turning said shaft in direction to retract the cam 29. Said cam 29 has a nose portion providing a stop surface 35 extending radially of the cam and also has a cam surface 36 extending risingly rearwardly from said stop surface 35.

The latch lever C is tiltable forth and back on 10 the pivot bolt 20 from an inoperative position, as shown in dotted lines in Fig. 1, to an operative position, as shown in solid lines in said Fig. 1. In the operative position of the latch lever C, its forward arm 21, through the catch 23 thereon, 15 engages and clamps the chase A in place on the bed 10 while in the inoperative position of said latch lever C, the said forward arm 21 thereof is stationed clear of the chase A and the path customarily followed in removing it from and placing it on the bed.

The cam 29 is movable forth and back about the axis of the cam shaft 32 from a retracted position, as shown in dotted lines in Fig. 1, to an advanced position, as shown in solid lines in said 25 Fig. 1.

A double-acting tension spring 37 is interposed between the forward arm 21 of the latch lever C and the cam 29, the front end of said spring 37 being caught on an anchoring pin 38 projecting 30 from the forward portion of said arm 21 and the rear end of said spring 37 being caught on an anchoring pin 39 projecting from the tail portion of said cam 29. Stretched between said anchoring pins 38, 39, the spring 37 is axially disposed above the axis of the pivot bolt 20 of the latch lever C and it tends not only to advance the cam 29 but also to tilt the latch lever C into the inoperative position thereof. When said latch lever C tilts in the direction of its said inoperative position under the action of said spring 37, the low bearing surface 26 of said latch lever comes into contact with the cam surface 36 of the cam 29 in the retracted position thereof thereby arresting such tilting of said latch lever C when it reaches its said inoperative position. In this position of the latch lever C, the riser-abutment 28 thereon is engaged by the stop surface 35 of the retracted cam 29, whereby said cam is held latched in its retracted position against the action of said spring 37. To unlatch the cam 29 from its retracted position and free it for advancement under the action of the spring 37, downward pressure of the operator's hand is brought against the end of the forward arm 21 of the latch lever C. This pressure of the hand initiates movement of said latch lever C from its inoperative to its operative position, thereby disengaging the riser-abutment 28 of said latch lever C from the stop surface 35 of the cam 29. Being rendered free to turn under the action of the spring 37, the cam 29 is advanced by said spring. Thereupon the cam surface 36 on said cam coacts with the high bearing surface 27 on the latch lever C, causing said latch lever to continue its tilting and forcing it into its operative position wherein the catch 23 clamps the chase A against the bed 10. Under the cam-advancing action of the spring 37, the latch lever C is reliably held firmly in chase-locking position, its grip on the chase A being intensified rather than weakened by vibrations occurring in the operating press. To release the latch lever C for tilting movement from its operative to the inoperative position thereof under the action of the spring 37, the finger piece 34 75

on the cam shaft 32 is manipulated to turn the cam 29 counter-clockwise, as seen in Fig. 1, from its advanced position to its retracted position.

From the foregoing, it is seen that in a printing press fitted with an embodiment of my invention, a pressman with a simple movement of either hand can readily cause the chase-locking latch lever C to be tilted into its inoperative position and likewise can cause said latch lever to be tilted into its operative position. Also it is seen that my invention is susceptible of embodiment in forms of simple, durable, inexpensive and efficient construction and in forms of unitary nature readily applicable to the beds of printing presses.

Changes in the specific form of the invention, as herein described, may be made within the scope of what is claimed without departing from the spirit of the invention.

Having described the invention, what is claimed 20 as new and desired to be protected by Letters Patent is:

1. A chase hook comprising a mounting adapted to be secured to the bed of a printing press, a latch lever pivoted on said mounting and tiltable from an operative position to an inoperative position and back again, said latch lever having a hooked forward arm and a rearward arm, said forward arm being adapted in the operative position of said latch lever to engage and clamp in place a chase operatively disposed on the bed of a press and adapted in the inoperative position of said latch lever to stand clear of the chase and the normal path of movement thereof to and from its place on the bed, the rearward arm of said latch lever having a low bearing surface rearwardly thereof, a high bearing surface forwardly of said low bearing surface and a riser-abutment between said bearing surfaces, a cam supported on said mounting for turning movement forwardly into an advanced position and rearwardly into a retracted position, said cam having a stop surface extending radially thereof and having a cam surface extending risingly rearward from said stop surface, a double-acting tension spring fastened at one end to the forward arm of the latch lever and at its other end to said cam, said spring tending both to advance the cam and to tilt said latch lever into its inoperative position, the low bearing surface of said latch lever being adapted to engage the cam surface of the retracted cam and arrest the tilting of the latch lever under the action of said spring when said latch lever reaches inoperative position, said stop surface on said cam being adapted in the retracted position of the cam and in the inoperative position of the latch lever to engage the riser-abutment on the latch lever and hold the cam retracted against the action of said spring, said riser-abutment being adapted to be disengaged from said stop surface by manually initiating movement of the latch lever toward its operative position thereby freeing the cam for advancement under the action of said spring, said cam surface of the cam being adapted when the cam is advanced to coact with the high bearing surface of the latch lever and force said latch lever into its said operative position, and means for manually retracting the cam against the action of said spring to free the latch lever for return to its inoperative position under the action of said spring.

2. A chase hook comprising a latch lever and a cam both being adapted to be mounted on the bed of a printing press, said latch lever being

ative position and back again and having a hooked forward arm and a rearward arm, said forward arm being adapted in the operative position of said latch lever to engage and clamp in place a chase operatively disposed on the bed of a press and adapted in the inoperative position of said latch lever to stand clear of the chase and the normal path of movement thereof to and from its place on the bed, the rearward arm of said latch lever having a low bearing surface rearwardly thereof, a high bearing surface forwardly of said low bearing surface and a riser-abutment between said bearing surfaces, said cam being adapted to be turned forwardly into an advanced position and rearwardly into a retracted position, said cam having a stop surface extending radially thereof and having a cam surface extending risingly rearward from said stop surface, spring means common to said latch lever and cam, said spring means tending to advance the cam and to tilt said latch lever into its said inoperative position, the low bearing surface of said latch lever being adapted to engage the cam surface of the cam in its retracted position and arrest the tilting of the latch lever under the action of said spring means when said latch lever reaches inoperative position, said stop surface on said cam being adapted in the retracted position of the cam and in the inoperative position of the latch lever to engage the riser-abutment on the latch lever and hold the cam retracted against the action of said spring means, said riser-abutment being adapted to be disengaged from said stop surface by manually initiating movement of the latch lever toward its operative position thereby to free the cam for advancement under the action of said spring means, said cam surface of the cam being adapted when the cam is advanced to coact with the high bearing surface of the latch lever and force said latch lever into its said operative position, and means for manually retracting the cam member against the action of said spring means to free the latch lever for return to its inoperative position under the action of said spring means.

3. A chase hook comprising a latch member and a cam both adapted to be mounted on the bed of a printing press, said latch member being movable forth and back from an inoperative position clear of a chase on the bed to an operative position engaging and clamping the chase in place on said bed, said cam being movable forth and back from a retracted position to an advanced position, a tension spring fashioned at one end thereof to the latch member and tending to move it into its said inoperative position, said spring being fastened at its other end to said cam and tending to advance the same, said cam having a cam surface, said latch member having a first bearing surface adapted to engage the cam surface of the retracted cam and arrest movement of the latch member under the action of said spring when said latch lever reaches its inoperative position, said cam having a stop surface, said latch member having an abutment thereon, said stop surface being adapted in the retracted position of said cam and in the inoperative position of said latch lever to engage said abutment and hold said cam retracted against the action of said spring, said abutment being adapted to be disengaged from said stop surface by manually initiating movement of the latch member toward its operative position thereby to free the cam for advancement under the action of said spring, said latch member having a sec-

ond bearing surface, said cam surface being adapted to coact with said second bearing surface upon the advancement of the cam and force said latch member into its said operative position, and means for manually retracting the cam against the action of said spring to free the latch member for return to its inoperative position under the action of said spring.

4. A unitary chase hook structure adapted to be mounted on the bed of a printing press, said structure comprising a latch member and a cam, said latch member being movable forth and back from an inoperative position clear of a chase on the bed to an operative position engaging and clamping the chase in place on said bed, said cam being movable forth and back from a retracted position to an advanced position, spring means acting upon the latch member and tending to move it into its said inoperative position, spring means acting upon the cam and tending to advance the same, said cam having a stop surface, said latch member having an abutment thereon, said stop surface being adapted in the retracted position of said cam and in the inoperative position of said latch lever to engage said abutment and hold said cam retracted against the action of the spring means tending to advance it, said abutment being adapted to be disengaged from said stop surface by manually initiating movement of the latch member toward its operative position thereby to free the cam for advancement, said latch member having a bearing surface, said cam having a cam surface adapted to coact with said bearing surface upon advancement of the cam under the action of the spring means tending to advance it and thereby force said latch member into its said operative position, and means for manually retracting the cam against the action of said spring means tending to advance it thereby to free the latch member for return to its inoperative position under the action of the spring means tending so to move said latch member.

5. A chase hook comprising a latch member and a cam both being adapted to be mounted on the bed of a printing press, said latch member being movable forth and back from an inoperative position clear of a chase on the bed to an operative position engaging and clamping the chase in place on said bed, said cam being movable forth and back from a retracted position to an advanced position, a tension spring fastened at one end thereof to the latch member and tending to move it into its said inoperative position, said spring being fastened at its other end to said cam and tending to advance the same, said cam having a stop member, said latch member having a stop element adapted in the retracted position of said cam and in the inoperative position of said latch lever to coact with the stop member of said cam and hold the cam retracted against the action of said spring, said stop element being adapted to be disengaged from said stop member by manually initiating movement of the latch member toward its operative position thereby to free the cam for advancement under the action of said spring, said latch member having a bearing surface, said cam having a cam surface adapted to coact with said bearing surface upon the advancement of the cam and force said latch member into its said operative position, and means for manually retracting the cam against the action of said spring to free the latch member for return to its inoperative position under the action of said spring.

6. A chase hook comprising a latch member and a cam both being adapted to be mounted on the bed of a printing press, said latch member being movable forth and back from an inoperative position clear of a chase on the bed to an operative position engaging and clamping the chase in place on said bed, said cam being movable forth and back from a retracted position to an advanced position, spring means common to said latch member and cam, said spring means tending to move the latch member into its said inoperative position and tending to advance the cam, said latch member in the inoperative position thereof being adapted interlockingly to engage the retracted cam and hold it retracted against the action of said spring means, said latch member being adapted to be disengaged from said cam by manually initiating movement thereof toward its operative position thereby to free the cam for advancement under the action of said spring means, said cam upon the advancement thereof being adapted to coact with said latch member and force it into its said operative position, and means for manually retracting the cam against the action of said spring means to free the latch member for return to its inoperative position under the action of said spring means.

7. A chase hook comprising a latch member and a cam, both thereof being adapted to be mounted on the bed of a printing press, each thereof for movement relative to the other, said latch member being movable forth and back from an inoperative position clear of a chase on the bed to an operative position engaging and clamp-

ing the chase in place on said bed, said cam being movable forth and back from a retracted position to an advanced position, yielding cam-moving means tending to advance the cam, said latch member having an abutment thereon, said cam having an abutment-engaging element thereon adapted in the retracted position of the cam and in the inoperative position of the latch member to engage the abutment on said latch member and hold the cam retracted against the action of said yielding means, said abutment on said latch member being adapted to be disengaged from said abutment-engaging element on said cam by moving the latch member toward its operative position, such disengagement of said abutment from said abutment-engaging element freeing the cam from the latch member for the advancement of said cam under the action of said yielding means, said latch member having a bearing surface, said cam having a cam surface adapted to coact with said bearing surface upon advancement of the cam thereby to force said latch member into its said operative position, and means for retracting the cam against the action of said yielding means to free the latch member for the return thereof to its inoperative position.
